UNITED STATES PATENT OFFICE.

HARRY B. JAY, OF AURORA, ILLINOIS.

MUTE FOR TRUMPETS, CORNETS, AND LIKE WIND INSTRUMENTS.

1,114,886.

Specification of Letters Patent. Patented Oct. 27, 1914.

Application filed May 12, 1913. Serial No. 767,075.

To all whom it may concern:

Be it known that I, HARRY B. JAY, a citizen of the United States, residing at Aurora, Illinois, have invented certain new and useful Improvements in Mutes for Trumpets, Cornets, and like Wind Instruments, of which the following is a specification.

This invention relates to improvements 10 in mutes for trumpets, cornets, and like wind instruments.

Mutes for wind instruments now commonly employed, unless made especially for the particular instrument, quite frequently 15 change the key as well as the character of the tone of the instrument; in other words, when the mute is used, the instrument is more or less out of tune.

It is the main object of my invention to 20 provide an improved mute for wind instruments of this class, which may be adjusted to the particular instrument, so that the instrument will be in tune when used with or without the mute; further, to provide an 25 improved mute having these advantages, which is simple in structure and adjustment and may be quickly applied to or removed from the instrument after once having been adjusted or tuned thereto.

Further objects, and objects relating to 30 structural details, will definitely appear from the detailed description to follow.

I accomplish the objects of my invention by the devices and means described in the 35 following specification.

The invention is clearly defined and pointed out in the claims.

A structure which is a preferred embodiment of my invention is clearly illustrated 40 in the accompanying drawing forming a part of this specification, in which:

Figure I is a side view of a cornet with my improved mute applied thereto, a portion 45 of the bell of the instrument being shown in longitudinal section. Fig. II is a longitudinal section of my improved mute, taken on a line corresponding to line 2—2 of Fig. I. Fig. III is an enlarged cross section on a line corresponding to line 3—3 of Fig. II. Fig. IV is an enlarged detail longitudinal section on a line corresponding to line 4—4 of Fig. III. Fig. V is a detail longitudinal central section of a modified construction, the modification being in the

means for effecting the adjustment of the 55 mute.

In the drawing similar reference characters refer to similar parts throughout the several views, and the sectional views are taken looking in the direction of the little 60 arrows at the ends of the section lines.

Referring to the drawing, the cornet or instrument 1 is shown mainly in conventional form and for the purpose of illustrating the manner of using my improved mute. 65

My improved mute consists of an inner tubular member 1 and an outer tubular member 2 arranged to telescope one within the other. The member 1 is provided with a gasket 3 at its inner end which fits into 70 the throat of the instrument to support the mute and close the throat. The outer member 2 is provided with a bell 4 having an end wall 5. The end wall has a central opening 6 in which the tube 7 is slidably 75 disposed. The outer end of the inner member 1 is provided with longitudinal slots 8 and is tapered and threaded to receive the clamping ring or nut 9. By means of this clamping ring or nut 9, the members are secured in their adjusted relation. The member 2 is formed of two sections joined by the collar 10 which also serves as a stop. The tube 7 is for the purpose of changing 80 the volume of the tone.

In the modification shown in Fig. V, the members are threaded together, the threads being spun therein. This manner of adjusting is quite satisfactory as it is found that there is sufficient friction between the members to retain them in their adjusted position. 85

In the use of the mute, it is adjusted to the particular instrument in which it is to be used so that the pitch of the instrument 90 is not changed by the use of the mute, and is clamped or secured in that position.

My improved mute, when in position in an instrument, has an air tight connection to the bell of the instrument and becomes a 100 part thereof, and it is possible to adjust the mute to the correct length for various diameters of bells when used on instruments of this class. For instance, in a bell of large diameter, the outer end wall of my improved 105 mute with the tuning slide closed, would enter too far, shortening the vibrating column of the air, thus making the instrument

higher in pitch when the mute was in position than it would be without the mute. In case of an instrument with bell of small diameter, my improved mute adjusted to an instrument with a bell of larger diameter, would make the column of air too long and consequently the pitch too low. By the tuning slide feature described, the mute can be adjusted for a particular instrument so that 10 the pitch of the instrument is not changed when the mute is in use. The pitch or tuning adjustment is entirely in the tuning slide or adjustment connection between the outer member 2 having the bell thereon and the 15 inner member. To apply the mute when thus adjusted, it is only necessary to insert it into the instrument, no further tuning adjustment being required.

My improved mute is very simple in structure and adjustment, and at the same time, 20 is very desirable in that it can be adjusted to the particular instrument with which it is to be used.

I have illustrated my invention in a practical embodiment. Various modifications 25 are possible other than that illustrated, but I have not attempted to illustrate or describe such modifications, as I believe the disclosure made will enable those skilled in 30 the art to apply or embody the same as may be desired and to meet the requirements of the particular case. I desire, however, to be understood as claiming my improvements specifically in the form illustrated, as well as 35 broadly within the scope of the appended claims.

Having thus described my invention, what I claim as new and desire to secure by Letters Patent is:

40 1. A mute for wind instruments of the class described, comprising a tubular inner member having a gasket on its inner end

adapted to fit the throat of the instrument, whereby the mute is supported therein and the throat is closed, the outer end of the inner member being longitudinally slotted, tapered and threaded; a tubular outer member adapted to telescope into said inner member and having a bell at its outer end provided with an end wall having a central opening therein; a clamping nut for said inner member whereby the members are secured in their adjusted relation; and a slide tube arranged in said opening in the outer end of said outer member to telescope into 55 the same.

2. A mute for wind instruments of the class described, comprising a tubular inner member adapted to be inserted into and close the throat of the instrument; a tubular outer member adapted to telescope with said inner member and having a bell at its outer end provided with an end wall having a central opening therein; means for securing said members in their adjusted relation; and 60 a slide tube arranged in said opening in the outer end of said outer member to telescope into the same.

3. A mute for wind instruments of the class described comprising an inner tubular member adapted to fit and close the throat of the instrument, an outer tubular member adapted to telescope into said inner member and having a bell at its outer end provided with an end wall having a central opening 70 therein, said members being adjustably associated for the purpose specified.

In witness whereof, I have hereunto set my hand and seal in the presence of two witnesses.

HARRY B. JAY. [L. S.]
